Primary Examiner — Austin Murphy(74) *Attorney, Agent, or Firm* — Standley Law Group LLP; Jeffrey S. Standley; Adam J. Smith(57) **CLAIM**

The ornamental design for an electronic display assembly, as shown and described.

DESCRIPTION

FIG. 1 is a front perspective view of the electronic display assembly;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

The broken lines illustrate unclaimed portions of the electronic display assembly.
